UNITED STATES PATENT OFFICE

2,460,617

PLANETARY PISTON FUEL PUMP

Roy O. Balogh, Cleveland, Ohio, assignor to The Weatherhead Company, Cleveland, Ohio, a corporation of Ohio

Application November 10, 1944, Serial No. 562,768

3 Claims. (Cl. 103—132)

1

This invention relates to rotary pumps.

Certain pumps have been proposed embodying a rotary runner or ring caused to travel about the cylindrical wall of a pump chamber and a spring-pressed vane reciprocably mounted in a well in the pump chamber between the inlet and outlet openings and slidably engaging the surface of the runner. This arrangement is objectionable, not only because of the initial cost of the spring-pressed vane assembly and the liability of the spring to breakage and displacement in service, but because of leakage at the joint between the free end of the vane and the runner. The principal objects of this invention are to eliminate these difficulties; to increase the efficiency of pumps of this type by effectively sealing the joint between the vane and the runner; and to simplify and reduce the cost of pumps of this type while increasing the durability and minimizing the requirements for service and repairs.

Other objects of this invention are to maintain a uniform pressure of the runner against the cylindrical wall of the pump chamber, while allowing reasonable manufacturing tolerances and avoiding the danger of excessive pressure or breakage of the parts in the event grit or solid matter should be caught between the runner and the cylindrical wall of the pump chamber; to maintain such uniform pressure without the use of springs or the like in the driving mechanism for the runner; to increase the efficiency of the pump by improving the seal between the runner and the walls of the pump chamber; and to reduce the cost and service requirements and increase the durability of the runner and driving mechanism of the pump.

In the accompanying drawings which illustrate the preferred embodiments of the present invention:

Fig. 1 is a transverse vertical section of the preferred embodiment of this invention taken on the line 1—1 of Fig. 2;

Fig. 2 is a transverse vertical section taken on the line 2—2 of Fig. 1;

Fig. 3 is a vertical section of the runner and vane taken on the line 3—3 of Fig. 2;

Fig. 4 is a side elevation of the runner and vane;

Fig. 5 is a transverse sectional view through a modified embodiment of the invention;

Fig. 6 is a transverse section through the ring and vane of the pump shown in Fig. 5; and

Fig. 7 is a side elevation of the runner and vane of Fig. 5.

The embodiment shown in Figs. 1 to 4 includes a pump housing or casing 5 provided with a cy-

2

lindrical pump chamber 6. Two passageways 7 and 8 are provided from the chamber 6. Each passageway may be connected to a pipe through which the fluid is conveyed, and either passageway may be the inlet or outlet, depending upon the direction of rotation of the runner.

A shaft 9 is journalled in the housing on the axis of the cylindrical pump chamber 6, and has a cam 10 eccentrically disposed thereon. A runner 11 in the form of a ring of metal or other suitable material is journalled on the cam 10 and is given an orbital movement around the wall of the pump chamber by rotation of the driving shaft 9. A vane 12 which may be metal or other suitable material is slidably disposed in a well 13 which extends radially from the cylindrical chamber 6 midway between the passages 7 and 8. The runner 11 is coated on its periphery with a layer 14 of rubber or other suitable resilient material which laps over the end edges of the runner 11 as shown in Fig. 2 and extends outwardly to embrace the opposite ends of the vane 12, as indicated at 15 in Fig. 3.

The runner 11 with the resilient layer 14 thereon constitutes an annulus having a diameter substantially shorter than the diameter of the cylindrical chamber 6. The cam 10 is arranged to engage the inner surface of the runner 11 and to yieldably press the resilient layer 14 against the cylindrical wall of the chamber 6. The vane 12 is spaced from the runner 11 a substantial distance so that the resilient material is disposed between the end of the vane and the outer surface of the runner 11. The well 13 is flared outwardly as indicated at 16 to receive the extension 15 of the resilient layer 14. Preferably the portion 16 is flared outwardly at a greater angle than the resilient portion 15 so as to permit the resilient portion 15 to move laterally a short distance.

The material of the resilient layer 14 also may be extended along the end edges of the vane 12, as indicated at 17. Preferably the axial length of the resilient layer 14, including the portions overlapping the end edges of the runner 11, is slightly greater than the axial length of the chamber 6 when the pump is assembled, so that the annulus consisting of the runner 11 and the resilient layer 14 is pressed against the opposite end walls of the pump chamber. Similarly the width in the axial direction of the vane 12 and the overlapping resilient portions 17 is slightly greater than the corresponding dimension of the well 13.

The portions 14, 15 and 17 may be made from natural or synthetic rubber or other elastomer. A suitable material is selected which is resistant

to the material to be pumped. This material is preferably vulcanized or similarly bonded in place about the runner 11 and to the end portions of the vane 12. Thus the runner vane and resilient layer 14 becomes in effect an integral unit although by reason of the spacing of the end of the vane 12 from the runner 11 and the resilient nature of the material 15 the vane 12 is free to oscillate in either direction from a true radial position with respect to the vane 11.

In operation the shaft 9 is driven in any suitable way and the passages 7 and 8 are connected to the lines through which it is desired to pump the fluid. When the shaft 9 is rotated in a clockwise direction as seen in Fig. 1, the passage 8 constitutes the inlet, and 7 the outlet, of the pump. As the shaft 9 turns from the position of the parts as seen in Fig. 1, the cam 10 slides within the runner 11 and the resilient layer 14 tends to roll about the cylindrical wall 6 of the pump chamber. Rotation of the runner 11 about its own axis, however, is prevented by the attachment thereto of the vane 12 which is free for reciprocating movement only in the well 13. Thus the resilient layer 14 slides to a limited extent around the inside of the cylindrical wall 6, the vane 12 being rocked first in one direction and then in the other direction from a true radial position with respect to the runner 11.

The pumping space is effectively sealed in a radial direction by the contact of the resilient layer 14 with the opposite end walls of the pump chamber 6. Leakage from the high pressure to the low pressure side past the vane 13 is prevented by the resilient material 15 bonded to the inner end of the vane 12. Leakage around the ends of the vane 12 is prevented by the resilient material 17 engaging the opposite ends of the well 13. Leakage through the well 13 is effectively prevented by the close engagement of the sides of the vane 12 with the well and the relatively large area of engagement between the vane and well. Leakage from the high pressure to the low pressure side past the area in the periphery of the runner which is engaging the cylindrical wall of the chamber 6 at any particular time is prevented by the pressure of the resilient layer 14 against the cylindrical wall, the magnitude of which may be predetermined by the relative proportions of the parts, depending upon the pressure which it is desired to develop in the particular pump. While the parts are made to press the layer 14 against the cylindrical wall of the pump chamber, any slight eccentricity of the parts resulting from manufacturing tolerances, and any grit or solid material that may be trapped between the moving parts, are prevented from creating excessive pressures or breaking or scoring the engaging members by reason of the yieldability of the resilient layer 14.

In the embodiment shown in Figs. 5, 6 and 7, the housing 25 is provided with a cylindrical pump chamber 26 and inlet and outlet openings 27 and 28. A driving shaft 29 is journaled in the housing on the axis of the cylindrical chamber 26 as in the embodiment previously described. The shaft 29 is formed with a squared portion 30 within the pump chamber 26 which slidably fits in a slot 31 extending diametrically into a cylindrical follower 32. A ball bearing consisting of an outer race 33, an inner race 34, and a series of balls 35 is fitted over the follower 32 with the outer race 33 engaging the cylindrical wall of the pump chamber 26. A spring 36 is seated in the slot 31 in the follower 32 and presses

against the squared portion 30 on the shaft 29, so as normally to urge the inner race 34 into an eccentrically offset position with respect to the shaft 29, as illustrated in Fig. 5.

- 5 A vane 37 is slidably mounted in a well 38 extending radially from the pump chamber 26 between the inlet and outlet passages 27 and 28. The inner end of the vane 37 is spaced a short distance from the periphery of the outer race 33.
- 10 A body of resilient material 39 such as natural or synthetic rubber or the like is bonded to the outer surface of the outer race 33 and to the inner end and the adjacent portions of the sides of the vane 37. Thus the vane 37 is sealed to the outer race 33 and is permanently connected thereto while being free to rock in either direction from a true radial position with respect to the race 33. In the operation of the pump illustrated in Figs. 5, 6 and 7, the outer race 33, as in the embodiment previously described, is caused to travel about the cylindrical wall of the pump chamber 26 but is prevented from rotating on its own axis by reason of its connection to the vane 37 which is radially slidably in the well 38. The outer race 33 is pressed against the cylindrical wall of the pump chamber 26 by the spring 36 but is yieldable to pass over any inequalities or solid material because of the slide fit of the follower 32 over the squared portion 30 of the shaft. The leakage from the high pressure side to the low pressure side of the pump past the vane 37 is prevented by the material 39 which is preferably vulcanized or similarly bonded to the parts so as to seal the joint between the vane 37 and the outer race 33. Leakage between the axial ends of the race 33 and the end walls of the pump chamber is minimized by simply maintaining a close fit between the parts in this direction. Leakage from the high pressure side to the low pressure side past the point of contact of the race 33 with the cylindrical wall of the chamber 26 is prevented by the tension of the spring 36 which presses the outer race 33 against the cylindrical wall.
- 45 Although preferred embodiments of the invention have been described in considerable detail it will be understood that the invention is not limited to the particular forms disclosed. For example, the ball or roller bearings, as shown in Fig. 5, to transmit the drive from the shaft to the runner may be used in the embodiment shown in Figs. 1 to 4, inclusive, when it is desired to minimize the friction, and similarly the follower 32 in Fig. 5 may be caused to slidably engage directly within the runner after the manner of the cam in Fig. 1 if the elimination of friction is not of sufficient importance to justify the cost of bearings in the particular installation. Manifestly, many other variations and rearrangements may be resorted to without departing from the scope of the invention as defined in the following claims.
- 65 I claim:
1. A rotary pump comprising a housing formed with a substantially cylindrical chamber, a recess extending radially outward therefrom and a port on each side of the recess, a shaft arranged axially in the chamber, a cam on the shaft, a ring journaled on the cam for orbital movement in spaced relation to the walls of the chamber, a vane formed of material as rigid as that of the housing, said vane extending substantially for the full depth of the recess, and a unitary resilient covering for the ring bonded to the vane, said
- 70
- 75

covering providing a restricted flexible connection between said ring and said vane.

2. A rotary pump comprising a metallic housing formed with a substantially cylindrical chamber, a recess extending radially outward therefrom and a port on each side of the recess, a shaft arranged axially in the chamber, a cam on the shaft, a ring journalled on the cam for orbital movement in spaced relation to the walls of the chamber, a vane of thin metallic material extending substantially for the full depth of the recess, and a unitary resilient covering for the ring bonded to the vane, said covering providing a restricted flexible connection between said ring and said vane.

3. A rotary pump comprising a metallic housing formed with a substantially cylindrical chamber, a recess extending radially outward therefrom and a port on each side of the recess, a shaft arranged axially in the chamber, a cam on the shaft, a ring journalled on the cam for orbital movement in spaced relation to the walls of the chamber, a vane of thin metallic material ex-

5 tending substantially for the full depth of the recess, and a unitary resilient covering for the ring bonded to the vane, said covering having an integral resilient extension for providing a restricted flexible connection between said ring and said metallic vane.
